UNITED STATES PATENT OFFICE.

WILLIAM MARTIN HUGHES, OF ARNCLIFFE, NEAR SYDNEY, NEW SOUTH WALES,
AUSTRALIA.

CARBURETER.

1,264,935.

Specification of Letters Patent.

Patented May 7, 1918.

Application filed April 22, 1918. Serial No. 92,835.

To all whom it may concern:

Be it known that WILLIAM MARTIN HUGHES, subject of the King of Great Britain and Ireland, residing at "Anona," Gipps 5 street, Arncliffe, near Sydney, New South Wales, Australia, has invented certain new and useful Improvements in Carbureters, of which the following is a specification.

This invention relates to carbureters for 10 air-gas making machines of the type in which volatile oil or oil spirit is supplied and distributed over an extensive surface above which surface air at normal temperature undergoing carburetion is caused to 15 pass.

According to this invention the carbureter comprises a number of nearly horizontally disposed superposed closed shallow pans or traps containing wire gauze 20 packing and connected together at alternate ends in zig-zag order. These pans or trays are slightly inclined relative to true horizontal position in order to cause a delayed lingering flow of the carbureting oil or oil 25 spirit in the same direction as the air current which passes through them, and to hold a limited quantity of oil or oil spirit to be retained in them.

In the accompanying drawings:

30 Figure 1 is a perspective sectional view of an air-gas machine and spring drive motor operating the same;

Fig. 2 is a transverse section through the gas bell and the carbureter which is 35 contained within it;

Fig. 3 is another section through the said bell showing the carbureter in end elevation and certain details of construction in section.

40 10 is a spring drum, and 11 a gang of spiral springs mounted on the fixed axle 12 thereof. Said drum 10 drives a fusee barrel 13 by means of a flexible rope 14. 15 is a manual rewinding crank geared (as 45 partially shown at 16) to the fusee barrel 13. Multiple gearing 17 with overrunning click clutch connects the fusee barrel to the sprocket wheel 18 and said wheel, through a chain belt 19 and sprocket 20, turns the 50 shaft 21 of the air forcing machine 22. The machine 22 is of an ordinary type commonly used in connection with air-gas making machines. On the shaft 21 a multiple cam 23 is keyed; this cam coacts with a pawl lever 55 24, which is reciprocated as each cam face

passes over its contact end. The pawl lever 24 is connected to plunger rod 25 working through a stuffing box 26 in the upper end of a pump barrel 27. A helical spring 28 in compression keeps the pawl 24 in contact 60 with the face of the cam 23, and an adjusting nut 29 serves to set the lever so as to limit the range of movement of the plunger rod 25 at each contact of the cam. The foot of the barrel 27 is connected into a well 65 30. The lower end of a stand pipe 31 is fitted into this well, and an oil feed pipe 32 is connected into the upper end of the pipe 31. 33 is a check valve which passes oil from the oil tank 34 to the pipe 32 but 70 not reversely. 35 is a check valve which passes oil upwardly only from the pump into the oil service pipe 36. The service pipe 36 is brought up through the bottom of the water well 37, as shown at 38, and its 75 upper end is returned into the trap chamber 39 which is charged with sufficient mercury to form a seal. From the head 40 of this trap chamber the oil passes through the pipe connection 41 into the uppermost pan 80 or tray of the carbureter. 42 is a float bell, forming with the water well 37 a gas container within which the carbureter is installed. The carbureter is immersed in the water in the well 37 and liability to freezing under cold working conditions thus minimized. The carbureter may be set up externally to the gas container. Air from the air pump 22 is forced through the air service pipe 42 into the top of the carbureter at 85 43 and passes down through the several trays of the carbureter successively in the same direction as the volatile oil which is delivered into the carbureter as before stated through the pipe connection 41. 90 Water and unvolatilized residual liquid from the foot of the carbureter may be drawn off through the foot valve 43. Carbureted air is taken from the lowest tray of the carbureter through the stand pipe 44, the upper end of which is above water level in the well 37. At the top of this pipe 44 95 a valve seating 45 is fitted, and a valve 46 works in this seating so as to close same when lifted; said valve is operated by a lever 47 which is connected by a chain 48 to the crown 49 of the bell 43. 50 is the gas reduction pipe; its upper end stands above water level, in the water well 37, and its lower end is brought out through the bot- 100 105 110

tom of the water well and is fitted with a control valve 51, whence a pipe 52 conveys gas to the place of use. 53 is a guide of any suitable type for maintaining verticality of 5 movement of the bell 42.

The carbureter comprises a number of shallow closed pans or trays of rectangular form connected together at alternate ends to form a zig-zag with the courses thereof located one above the other and disposed nearly horizontally, with the connections disposed vertically. These pans or trays and their end connections are constructed of sheet metal; each pan or tray is loosely 10 packed with fine wire gauze corrugated or crimped up as shown at 60 transversely of the direction of air and oil through the trays.

The first tray 61 is set on a considerable downward inclination, and the second tray 20 62 is set approximately horizontally in the direction of its length. Thereafter to the lowermost tray of the series, the succeeding trays are set more or less inclined to the horizontal the angularity increasing gradually 25 toward the bottom of the carbureter. The inclination is upward from the point of entry of the oil to the point of overflow of same into the next tray below. The first tray 63 below the horizontal tray 62 is almost 30 horizontal but is inclined very slightly upwardly in the direction shown by the arrow above it. The next tray 64 is inclined upward in the opposite direction at a slightly greater angle, as shown by the arrow 35 above it, and so on for each succeeding tray 65, 66 67 and 68, the lowermost tray 69 being horizontal and terminating in a foot box 70 from which surplus oil may be drawn off through the foot valve 43.

40 The method of operation is as follows:—

The spring motor being wound or other means supplied to rotate the shaft 21, air is forced by the pump 22 through the air pipe 42 and inlet 43 into the top tray 61 of 45 the carbureter. As the shaft 21 rotates, carrying with it the cam 23, the pawl 24 is reciprocated and the plunger moved in the pump barrel 27, the range of stroke being determined by the adjustment of the nut 29.

50 The movement of the plunger in the pump barrel 27 causes surging to and fro of mercury contained in the foot box 30, each downward movement of the plunger forcing the mercury up in the stand pipe 31 and so 55 forcing oil out of said stand pipe 31 through the check valve 35 and through the pipe 36 into the top of the carbureter at the connection 41. At each reverse movement of the pump plunger the mercury in the foot box 30

60 is drawn back into the barrel 27, with the result that another charge of oil is drawn into the pipe 31 from the oil reservoir 34 through the check valve 33. The quantity of oil 65 delivered to the carbureter during each revolution of the air drum is thus con-

trolled by adjusting the nut 29. Mercury contained in the trap 39 insures immediate service of oil to the carbureter when the machine is started up. The oil which passes up through the pipe 36 is forced through the mercury in the trap 39, and thence, passing through the stand pipe 40, goes through the connection 41 into the top of the carbureter as before stated. Air and oil are thus supplied simultaneously into the top tray 61 of the carbureter. As the oil flows downward it films the surface of the tray 61, thence passing into the tray 62 it films its surface and in that tray and in succeeding trays also charges the meshes of wire 75 gauze 60 so that a very large vaporizing surface through and over which the air passes is maintained in an oil filmed condition. A shallow body of oil is retained in the lower portion of each of the trays 63 to 68, and is 80 replenished constantly in each of those trays by oil which overflows from the preceding trays respectively, and the oil feed is regulated by adjusting the nut 29 so that a negligible quantity of vaporizable oil finds its 85 way to the foot box 70, practically the whole of the feed being vaporized and taken up by the air in passing through the circuit of trays from the inlet 43 to the delivery pipe 44. If the gas obtained with this 90 adjustment is found to be too rich a further adjustment of the nut 29 serves to diminish the feed of oil per unit volume of air, and in this way any required dilution of the gas may be arranged while the machine is in 95 operation. When the inflow into the bell 42 has so far exceeded the demand that the bell has lifted to its top position, the lever 47 is lifted by means of the chain 48 and the valve 46 closed, which happening, the inflow of air 100 is checked and the air pump 22 is brought to rest until gas is again drawn from the bell.

In the drawing the size of the spring motor relative to the gas holder and carbureter has been exaggerated to facilitate illustration of the necessary detail.

What I claim as my invention and desire to secure by Letters Patent is:—

1. In an air gas making machine, a carbureter comprising a series of communicating 115 closed flat bottomed trays arranged with each succeeding tray lower than the preceding, and the intermediate trays inclined upwardly in the direction of flow through them; means for introducing air and volatile oil under pressure into the uppermost 120 of said trays, and means for educting air-gas and liquid residue from the lowermost of said trays.

2. A carbureter for an air-gas making machine comprising a series of superposed closed flat bottomed trays or chambers connected in zig-zag order at alternate ends, whereof the trays or chambers intermediate in the series are inclined upwardly in the 125 130

direction of flow of air through them, the angles of inclination increasing progressively through the series, in combination with means for introducing air and volatile oil under pressure into the uppermost of said trays or chambers and means for educting air-gas and liquid residue from the lowest of said trays or chambers.

3. A carbureter for an air-gas making machine comprising a series of superposed closed flat bottomed trays or chambers packed with corrugated wire gauze slips, said trays or chambers connected in zig-zag order at alternate ends, and those intermediate in the series inclined upwardly in the

direction of flow of air through them, the angle of inclination increasing progressively through the series, in combination with means for introducing air and volatile oil under pressure into the uppermost of said trays or chambers and means for educting air gas and liquid residue from the lowermost of said trays or chambers.

In testimony whereof I have affixed my signature in presence of two witnesses.

WILLIAM MARTIN HUGHES.
